UNITED STATES PATENT OFFICE.

KARL AUG. JOHANSSON, OF CHICAGO, ILLINOIS, ASSIGNOR OF ONE-HALF TO
EDWARD H. WACHS, OF SAME PLACE.

AUTOMATICALLY-COMPENSATING JOURNAL-BOX.

SPECIFICATION forming part of Letters Patent No. 446,384, dated February 10, 1891.

Application filed November 24, 1890. Serial No. 372,479. (No model.)

To all whom it may concern:

Be it known that I, KARL AUG. JOHANSSON, a citizen of the United States of America, residing at Chicago, in the county of Cook and

- 5 State of Illinois, have invented certain new and useful Improvements in Automatically-Compensating Journal-Boxes, of which the following is a specification, reference being had therein to the accompanying drawings.
- 10 This my invention relates to journal-boxes of the kind in which alternately the bearing-strain is brought against opposite sides or ends, such as in boxes of pitmen and in main pillow-blocks for crank-shafts of engines,
- 15 &c., and in these boxes it is very important that with the least friction all lost motion be obviated, as otherwise with the reciprocating force or power exerted a jerking movement destructive to all machinery will be the consequence; and it is the object of this my invention to provide a device that automatically will take up all lateral movements and thereby compensate for any wear of the boxes; and with that object in view my invention principally consists of two disks having helical faces that are placed in contact in a manner that a rotating movement of the two disks in opposite directions will diminish or increase their total width and in a spiral
- 20 spring inserted between these disks and so connected with its ends to the adjoining disks to exert its force in a direction to increase the total width occupied by these disks, such disks so constructed being placed in the journal-bearing or pillow-block behind a movable brass or journal box, all as will be more fully hereinafter described, and specifically claimed.

In the accompanying drawings, Figure 1 represents an elevation of a pitman-head having my improved device, and Fig. 2 is a longitudinal section through the center of the same. Fig. 3 is a bottom or helical face view of the upper expansion-disk; Fig. 4, a side elevation of the spiral spring detached; and Figs. 5 and 6 are elevations of other parts detached.

Corresponding letters of reference in the several figures of the drawings designate like

A denotes the pitman-head providing a rectangular opening, into which the brasses B and C are fitted, which are bored each to form a semi-bearing for the crank-pin or cross-head pin of an engine. The brass B is fitted to be 55 rigid in the pitman-head, while the brass C can slide longitudinally in such head. With its lower or square end this brace C rests upon a plate D, having rectangular end flanges d, which are snugly fitted between 60 the side faces of the head-opening also to slide longitudinally therein, and against the bottom face of such head-opening is fitted a rectangular plate E.

Two disks F and G are fitted to have helical faces somewhat like the faces of a coupling-clutch, which when brought together will snugly fit upon each other, while their exterior faces are square to their cylindrical periphery, and the disk G has to its outer or 65 under face a projecting central boss g, that enters a central hole of plate E. The disk F has a central downwardly-projecting pin f, that enters a central hole in disk G for holding both disks on relative concentric positions, and around this pin f both disks have 70 annular recesses providing a chamber for a spiral-spring H, surrounding pin f, and having right-angularly bent ends inserted into any one of a series of sockets drilled into the 75 bottoms of the annular recesses of both disks F and G, so as to enable the placing of the spring H on any desired tension for rotating the disks in such opposite directions for the helix shoulders h to turn away from each 80 other, and thereby to increase the total width of both disks, whereby such disks will push and hold the brass C up to its bearing against the pin or shaft, compensating for all slack movement or lost motion that might be brought 85 about by frictional wear of the contacting surfaces in motion.

The disks F and G have drilled in their circumferential surface each a series of radial sockets i for inserting small levers of wire, 95 by which the said disks may be turned to contract the spring and thereby decreasing the total width of both disks combined; and the parts D, F, G, and E placed together with the spring thus contracted can be in- 100

serted into position, and then securely held in position by a plate I, secured against one side, and strips of metal J, secured against the opposite sides of plate D by screws J, tapped 5 into the right-angular flanges of plate D.

As will be readily seen, this device can be applied not only to pitman-heads, but also to pillow-blocks, and is reliable for making their bearings self-adjusting without any possibility of getting out of order.

What I claim is—

1. The combination, with a sliding brass or bearing, of disks F and G, having helical meeting faces, and a spring H for rotating such 15 disks in opposite directions, tending to increase their joint width, substantially as set forth.

2. The combination, with the solid frame of the kind specified and with one rigid and one 20 movable brass or bearing fitted therein, of disks F and G, inserted behind the movable brass or bearing and having helical meeting faces, and a spring inserted in a central recess between such disks, exerting its force

to rotate such disks in opposite directions, 25 and thereby tending to increase their joint width, substantially as and for the purpose set forth.

3. The combination, with head or box A, rigid brass B, and movable brass C, of plates 30 D and E, disks F and G, having helical meeting faces, and spring H, all constructed and arranged substantially as set forth.

4. The combination, with head or box A, rigid brass B, and movable brass C, of plates 35 D and E, disks F and G, connected by a pin f and having helical meeting faces, spring H, inserted in recesses between such disks, and plate I and strips J, secured against the sides of plate D, all constructed and arranged substantially as described, to operate as specified.

In testimony whereof I affix my signature in presence of two witnesses.

KARL AUG. JOHANSSON.
